CLAIM

(21) Appl. No.: **29/437,453**

The ornamental design for a thin renovation ceiling tile cover
for a blemished existing flat 2'×4' ceiling tile, as shown and
described.

(22) Filed: **Nov. 16, 2012**

DESCRIPTION

(51) **LOC (10) Cl. 25-01**

FIG. 1 is an upward perspective view showing my new design
for a thin renovation ceiling tile cover for a blemished existing
flat 2'×4' ceiling tile;

(52) **U.S. Cl.**

FIG. 2 is a bottom plan view;

USPC **D25/138**

FIG. 3 is a front side elevational view which is a mirror image
of the rear elevational view;

(58) **Field of Classification Search**

FIG. 4 is a top plan view;

USPC 52/39, 127.6, 127.8, 144, 145, 223.7,
52/243.1, 262, 282.2, 372, 375, 384, 385,
52/472, 506.06, 435, 314, 732; D25/58,
D25/138, 153, 156, 157, 163; 428/51

FIG. 5 is a left side elevational view which is a mirror image
of the right side elevational view; and,

See application file for complete search history.

FIG. 6 is a broken away cross sectional view.

(56) **References Cited**

The broken line drawings of the prior blemished existing flat
2'×4' ceiling tile and support grid are for illustrative purposes
only and form no part of the claimed design.
